[57] CLAIM

The ornamental design for a container for an oil filter or the like, substantially as shown.

DESCRIPTION

FIG. 1 is a top plan view of a container for an oil filter or the like showing my new design;

FIG. 2 is a side elevational view thereof;

FIG. 3 is a bottom view thereof; and

FIG. 4 is an enlarged cross-sectional view taken along line 4—4 of FIG. 2.
